(57) CLAIM

The ornamental design for a dish for laboratory use, as shown and described.

DESCRIPTION

FIG. 1 is a perspective view of a dish for laboratory use showing my new design;

FIG. 2 is another perspective view thereof;

FIG. 3 is a front view thereof, the rear view being identical to the front view;

FIG. 4 is a top view thereof;

FIG. 5 is a bottom view thereof; and,

FIG. 6 is a right side view thereof, the left side view being identical to the right side view.

The broken lines depict portions of the dish for laboratory use which form no part of the claimed design.
